UNITED STATES PATENT OFFICE.

CHARLES GILBERT HAWLEY, OF CHICAGO, ILLINOIS, ASSIGNOR TO CENTRIFIX CORPORATION, OF CLEVELAND, OHIO, A CORPORATION OF OHIO.

CENTRIFUGAL FIXTURE.

Application filed May 4, 1925. Serial No. 27,865.

My invention relates to separators or centrifugal fixtures for use in extracting or separating moisture and solids from steam, air and gas lines, and the like; and, the objects of the invention are to provide a combined centrifugal separator and drip pocket which shall be adapted for use in both horizontal and vertical lines or pipes and to provide a separator which shall be of simple, economical and convenient construction, which shall be of relatively small size and of little weight and highly efficient.

The structure embodying the invention and the manner in which the foregoing objects are attained will be clearly understood on reference to the drawing that forms part of this specification. In said drawing Fig. 1 is a vertical section of a centrifugal fixture embodying my invention as it appears when used in a horizontal line. Fig. 2 is a transverse section on the line 2—2 of Fig. 1, but on a reduced scale; Fig. 3 is a transverse section on the line 3—3 of Fig. 1; and Fig. 4 illustrates the use of the fixture in a vertical position.

The present invention is distinguished or characterized, first by a substantially cylindrical casing 2 which contains a hole 3 in one end, a hole 4 in the other end and a hole 5 in its side. In addition there is a hole 6 adjacent the hole 4, through which the heavier substances that are collected in a manner about to be described, are discharged. Preferably the casing is made in two parts, to wit, the main body part and the separable end 2', these parts being connected by the flanges shown and the bolts 7. The opening 6 is in the part 2' and leads tangentially from the circular bowl or cavity 8 therein. Between the shoulders 9 and 10 of the parts 2' and 2 are suitable packing rings and the larger metal ring 11. Obviously the latter is clamped in place when the bolts 7 are tightened. The ring contains a central hole 12 which is considerably larger than the outlet 4. By means of the ring 11 and the part 2' the bowl 8 is formed into a circular expansion race surrounding the openings 12 and 4. The part A is a fluid-whirling device, that is attached to the ring 11, and of which the ring 11 forms the base. Preferably the member 8 is of the same internal diameter at the hole 12 and comprises a circumferential series of operatively overlapping tangential tuyère blades

13 which form the many tangential slit-like tuyères 14, best shown in Fig. 2. The fluid enters in the direction of the arrow 15 and its direct passage through the ring or barrel A is prevented by the ring end or disk 16. Preferably the latter is integrally united with the casing 2 by arms 16' and its periphery 16'' is finished to receive the ring of blades 13.

The fluid which flows through the fixture enters the cavity 17 surrounding the multiple tuyère A and passes into the latter through its many tangential tuyères. Thereby the flowing liquid is set into very rapid rotation in a plane transverse to its longitudinal direction and by this operation the heavier substances are centrifugally collected upon the periphery of the whirling fluid body and are carried forward and centrifugally discharged into the race or bowl 8, leaving the purified fluid to depart through the outlet 4. For the reception of the heavier substances a closed pocket or trap is provided at the outer end of the tangential discharge opening or nozzle 6. The momentum of the heavier substances carries them through the nozzle and they settle in the trap 18. The latter may be emptied by any suitable means, working or worked at intervals.

In Fig. 1 the fluid supply pipe is shown at 3' and the outlet pipe at 4'. When thus used in a horizontal position the fixture is provided with a slug pocket 5', the end of which is fastened in the opening 5. When the fixture is used in a vertical position the supply pipe 5'' enters the opening 5 and the slug pocket 5' is installed at the end opening 3. The trap 18 remains as before, always hanging from the end of the nozzle 6.

This fixture may be found to be highly efficient and of very general utility.

Having thus described my invention I claim as new and desire to secure by Letters Patent:

1. A centrifugal separator comprising a casing having interchangeable inlet openings, in combination with a slug pocket installed at one of said openings, said casing having an outlet opening distant from the other openings, and a fluid separating member interposed within said casing.

2. A centrifugal separator comprising a casing having interchangeable inlet openings and a relatively distant outlet opening,

100

105

110

also an eject nozzle adjacent said outlet opening, in combination with a slug pocket installed at one of said inlet openings, and a trap installed at said nozzle.

3. A centrifugal fixture comprising a two part casing, one containing a cavity for the admission of the fluid and the other a bowl for the discharge of the fluid, the latter

having a peripheral discharge nozzle, and, a multiple tuyère ring of less diameter than 10 said casing and provided with a base ring which is clamped between the parts of said casing.

In testimony whereof I have hereunto set my hand this 30th day of April, A. D. 1925.

CHARLES GILBERT HAWLEY.
